UNITED STATES PATENT OFFICE.

HARVEY M. SMITH, OF MOORESVILLE, INDIANA, ASSIGNOR OF ONE-HALF TO DAVID HERZOG, OF MOORESVILLE, INDIANA.

EXPLOSIVE-MIXTURE HEATER AND DILUTER.

1,117,141.

Specification of Letters Patent. Patented Nov. 10, 1914.

Application filed April 28, 1913. Serial No. 764,042.

To all whom it may concern:

Be it known that I, HARVEY M. SMITH, a citizen of the United States, residing at Mooresville, in the county of Morgan and State of Indiana, have invented a new and useful Explosive-Mixture Heater and Diluter, of which the following is a specification, reference being had to the accompanying drawings and to the letters and figures 10 of reference marked thereon.

This invention relates to explosion engines using carbureted air as explosive mixture, the invention having reference more particularly to means for priming the engine in advance of the operation of the carburetor, and for heating and diluting the explosive mixture after the engine is in operation.

An object of the invention is to provide improved means whereby an explosion engine may be primed most economically, especially such as have an intake manifold supplying a plurality of cylinders with fuel.

A further object is to provide improved 25 priming apparatus that shall be so constructed that the priming medium shall be delivered as closely as possible to the explosion chambers and in the most effective condition.

A still further object is to provide improved means for heating and diluting the explosive mixture during operation of the engine in order to attain economy of fuel in operation.

Another object of the invention is to provide apparatus of the above mentioned character that shall be so constructed as to be adapted to be readily applied to automobiles now in use.

With the above mentioned and other objects in view, the invention consists in a plurality of controlling valves adapted to be connected to the branches of an intake manifold, devices for simultaneously operating 45 the valves, a plurality of warm-air pipes connected respectively to the controlling valves and adapted to be wound about the exhaust manifold of an explosion engine, two reservoirs for carrying and feeding 50 combustible liquid, and two feed pipes connected respectively to the reservoirs and to the warm-air pipes in a novel manner, the warm-air pipes having novel forms.

The invention consists also in the novel 55 parts and in the combinations and arrange-

ments of parts as hereinafter particularly described and claimed.

Referring to the drawings, Figure 1 is a fragmentary perspective view of a four-cylinder explosion engine and portions of an automobile to which the improvement is applied; Fig. 2 is a rear elevation of the engine and the warm-air pipes connected therewith; Fig. 3 is a fragmentary vertical section of the intake manifold and controlling valves connected therewith; Fig. 4 is a vertical section of one of the controlling valves in closed position on the line A A in Fig. 3 slightly enlarged; Fig. 5 is a section of the controlling valve on the line A A; Fig. 6 is a fragmentary sectional plan view approximately on the line B B in Fig. 2; Fig. 7 is a fragmentary vertical section of one of the warm-air pipes and feed pipe connected therewith; Fig. 8 is a fragmentary section approximately on the line C C in Fig. 1; Fig. 9 is a fragmentary horizontal section of the automobile dash-board and a top plan of the reservoirs; and Fig. 10 is a fragmentary section approximately on the line D D in Fig. 6.

Similar reference characters in the different figures of the drawings indicate corresponding elements or features of construction herein referred to.

The explosion engine to which the invention is applicable may comprise one or more cylinders and a suitable number of intake pipes or manifold branches, and the exhaust manifold may be variously arranged, it being designed to independently supply each intake pipe or manifold branch either with priming medium for starting the engine or warm air for increasing the efficiency of the explosive mixture commonly supplied for the cylinders after starting the engine. It is further designed that the apparatus may be adapted for supplying the priming medium to only one of the intake pipes or manifold branches if desired in order to conserve the supply of the priming liquid, such as gasoline.

The invention is comprehensively illustrated in connection with a four-cylinder engine and an automobile, the latter comprising a frame 1 and a dash-board 2, the engine comprising water jacketed cylinders 3 and 4 cast together and companion cylinders 5 and 6 cast together, the cylinders being mounted upon an engine frame 7. The

cylinders 3 and 4 are provided with a suitable intake valve chest 8, the cylinders 5 and 6 with a similar valve chest 9. The cylinders 3 and 4 are provided with a suitable 5 exhaust valve chest 10, the remaining cylinders with a similar exhaust valve chest 11. An intake pipe 12 has two branches 13 and 14 connected to the valve chests 8 and 9 respectively and is connected with a suitable 10 carbureter 15 and provided with a throttle valve 16 mounted on a shaft 17 provided with an operating arm 18 to which is connected a rod 19 extending through the dashboard so as to be reached by the operator. 15 The exhaust manifold comprises a main pipe 20 having branches 21 and 22 connected with the exhaust valve chests 10 and 11 respectively.

The improved apparatus as preferably 20 constructed comprises a suitable number of controlling valves, there being two in the present case, and provided with connecting nipples 23 and 23' having coupling nuts 24 and 24' thereon respectively whereby valve bodies 25 and 26 are detachably connected to the nipples respectively, one nipple being connected to the branch 13 and the other to the branch 14 of the intake manifold. The controlling valves are preferably 25 of the stop cock type and comprise rotary plugs 27 and 28 mounted in the bodies 25 and 26 respectively and provided with operating arms 29 and 30 respectively 30 to which a coupling rod 31 is connected for operating the plugs in unison, an operating rod 32 being connected to the coupling rod and extending through the dash-board 2 so as to be reached by the operator. The controlling valves are arranged as closely 35 as may be convenient to the intake valve chests so that the heated explosive mixture is not liable to become cooled before reaching the explosion chest. Two warm-air pipes are connected to the two controlling 40 valves respectively and preferably they are composed of annealed copper so that they may be bent as may be desired. One of the warm-air pipes is bent so as to form an upright portion 33 that is connected to the valve body 25, the pipe being bent so as to extend over laterally and downward and to form an arched portion 34 and a relatively lower portion 35 to which a pipe T 36 is connected. Another piece of pipe is so bent 45 as to be arched and its lower end portion 37 is connected to the T from which the pipe extends upward so as to have a relatively high portion 38 from which a reach portion 39 extends to the position of the 50 exhaust manifold around which the pipe is bent in the form of a coil 40, the terminal end 41 of which is brought nearly to the valve chest 10 so as to constitute the inlet end of the warm-air pipe to receive heated air from the surface of the engine. The

other warm-air pipe is somewhat similarly formed to constitute an upright portion 42 which is connected to the valve body 26 and is bent to form an arch 43 and a relatively low portion 44 to which is connected a 70 pipe T 45, another piece of pipe being bent to form a relatively low portion 46 that is connected to the T, the pipe being arched to form a relatively high portion 47 from which extends a reach portion 48, the pipe 75 being bent around the exhaust manifold 20 in the form of a coil 49 with its terminal end 50 brought over nearly to the exhaust valve chest 11 to serve as the inlet end for heated air. The arched portions 38 and 47 80 and the reach portions of the pipes are brought together and protected against radiation of heat by a cover 51. It should be understood that the T's are conveniently made use of for connecting feed pipes to the 85 warm-air pipes at relatively low portions of the warm-air pipes but that separate T fittings obviously are not a necessity, since the feed pipes may be otherwise connected to the warm-air pipes. 90

Two reservoirs 52 and 53 are provided and are secured to the dash-board 2 at a suitable height to provide gravity feed, the bottom of each reservoir having a feed duct 54 therein. A relatively small feed pipe 55 95 is connected preferably by means of a coupling nut 56 to the bottom of one of the reservoirs and is connected also to the T 45 by means of a nut 57, another feed pipe 58 being connected to the other one of the two reservoirs by means of a nut 59 and it is connected also to the T 36 by means of a nut 60, the coupling nuts being preferably employed so that the different parts may be conveniently shipped in knocked down condition. The interior of each reservoir has a screw-threaded bridge 61. Two valve stems 62 and 63 are provided for the respective reservoirs and each is screwed through the bridge 61 and has a needle pointed valve 64 100 on its end that controls the duct 54, the upper ends of the stems being provided respectively with controlling arms 65 and 66 to which operating rods 67 and 68 are connected, the rods extending through the dash-board 2 and provided with adjustable stop nuts 69 and 70 for adjusting the lift of the valves. Preferably a connecting bar 71 is secured to the two operating rods 67 and 68 and is provided with a handle 72, but in some cases the bar may be omitted in order that each feed valve may be operated separately and independently. Each reservoir has a top 73 thereon through which the reservoir is filled, each top having an aperture 74 therein, one top being normally closed by a cover 75 having an aperture 76 therein, the other by a cover 77 having an aperture 78. The valve stems extend through the tops and the covers and the lat- 105 110 115 120 125 130

ter may be rotated so as to bring the apertures therein fair with the apertures in the tops of the magazines.

In practical use suitable liquid such as 5 gasolene is carried in the two reservoirs, and when ready to start the engine the operator opens the controlling valves and slightly turns one or both of the feed valves so as to let a small quantity of gasolene flow 10 by gravity to the lower portion or sag of one or both of the warm-air pipes where the gasolene momentarily remains until the engine produces suction after being cranked or otherwise started. The suction draws air in 15 through the warm-air pipes and the air becomes carbureted by the gasolene while passing through the warm-air pipes to the explosion chambers of the engine, so that the engine at once receives explosive mixture in advance of the practical working of 20 the carbureter, or if the latter has begun to operate the explosive mixture is enriched to a greater extent than that furnished by the carbureter, so that the engine starts 25 promptly. After the engine is governed in the usual manner to drive the automobile it is usually found that the constituents of the explosive mixture are not accurately proportioned and that usually it is an advantage 30 to supply additional air, and that the air should be heated in order to heat the explosive mixture and thereby produce most efficient mixture. It is preferable that the controlling valves be closed after starting 35 the engine and until it is desirable or expedient to dilute the explosive mixture, and then it is only necessary to manipulate the operating rod 32 to open the controlling valves more or less as may be found best on 40 observation of the results attained, the admission of the heated air and its mixing with and heating the explosive mixture invariably resulting in increased speed of the engine. If the increase of speed is not desired then the amount of gasolene fed to the 45 carbureter may be reduced and saved.

Having thus described the invention, what is claimed as new is—

1. An explosion engine primer and mixture diluter including a controlling valve 50 provided with an operating device, an air-pipe connected at one end with the valve and having a depressed portion and two relatively elevated portions on opposite ends of the depressed portion, and means for admitting liquid to the depressed portion of the air-pipe.

2. An explosion engine primer and mixture diluter including a plurality of reservoirs, a plurality of controlling valves having each an operating-arm, an operating rod connected to the operating-arms of all the controlling valves, a plurality of air-pipes that are each open at one end and connected at the opposite end with the control-

ling valves respectively, a plurality of oil-feed pipes connected respectively to the reservoirs and the air-pipes, and valves for either independently or simultaneously admitting liquid from the reservoirs to the oil-feed pipes respectively. 70

3. An explosive mixture heater and diluter and engine primer including a valve casing, a valve rotatively mounted in the casing, a warm-air pipe connected at one 75 end to the casing and having a depressed or sag portion between two relatively elevated portions, the opposite end portion of the pipe being coiled, an oil-feed pipe connected to the depressed portion of the warm-air 80 pipe, a reservoir connected to the oil-feed pipe, and a valve in the reservoir.

4. An explosion engine primer and mixture diluter including a controlling valve having an operating-arm, an operating-rod 85 connected with the operating-arm, an air-pipe connected at one end with the controlling valve and having a depressed portion and two relatively elevated portions on opposite ends of the depressed portion, a feed 90 pipe connected to the depressed portion of the air-pipe, a reservoir connected to the feed-pipe, and a valve for admitting liquid from the reservoir to the feed-pipe.

5. An explosive mixture diluter and engine primer comprising a plurality of air-pipes, each air-pipe having two arched portions and a relatively low depressed or sag portion between the two arched portions, a plurality of controlling valves connected to 100 the air-pipes respectively at one end thereof, a plurality of oil-feed pipes connected to the depressed or sag portion of the air-pipes respectively, a plurality of reservoirs connected to the oil-feed pipes respectively, 105 and a plurality of valves in the reservoirs for opening communication with the oil-feed pipes respectively. 95

6. The combination with an explosion engine, and an intake pipe having a plurality 110 of branches connected with the explosion engine, of a plurality of controlling valves connected to the branches respectively adjacent to the explosion engine, the valves being provided with operating-arms respectively, a connecting-rod connected to all the operating-arms, a plurality of air-pipes connected with the controlling valves respectively, each air-pipe having a depressed portion between two relatively elevated portions, and a plurality of oil feed-pipes connected to the depressed portion of the plurality of air-pipes respectively. 115

7. The combination with an explosion engine, an intake comprising a plurality of 125 branches connected with the engine, and an exhaust pipe connected with the engine, of a plurality of controlling valves connected to the branches respectively and provided each with an operating-arm, an operating-rod 130

connected with all the operating-arms, a plurality of warm-air pipes connected with the controlling valves respectively and extending about the exhaust pipe, the warm-air pipes having portions that are in close arrangement each with the other, a covering extending about the closely arranged portions of the warm-air pipes, a plurality of oil feed-pipes connected to the warm-air pipes respectively, a plurality of reservoirs connected to the oil feed-pipes respectively, and a plurality of valves having a common operating device for simultaneously opening communication from the reservoirs to the respective oil feed-pipes.

8. The combination with an explosion engine, an intake pipe having a plurality of branches connected with the engine, and an exhaust pipe connected with the engine, of a plurality of controlling valves connected to the branches respectively adjacent to the engine, the valves being provided with operating-arms respectively, a coupling rod con-

nected to all the operating-arms, an operating-rod connected with the coupling-rod, a 25 plurality of warm-air pipes connected with the controlling valves respectively and extending about the exhaust pipe, the warm-air pipes having each a depressed portion and two relatively elevated portions on opposite ends of the depressed portion, a plurality of oil-feed pipes connected to the depressed portion of the warm-air pipes respectively, a plurality of reservoirs connected to the oil-feed pipes respectively, and a 30 35 plurality of valves for opening communication from the reservoirs to the oil-feed pipes respectively and provided each with an operating-rod.

In testimony whereof, I affix my signature 40 in presence of two witnesses.

HARVEY M. SMITH.
